REFRIGERATED SHOWCASE

Hubert D. Sandeffer, Anaheim, Calif., assignor to Weber Showcase & Fixture Co., Inc., Los Angeles, Calif., a corporation of Delaware

Filed Sept. 14, 1962, Ser. No. 71,706

Term of patent 14 years

(Cl. D80—11)

I claim:

The ornamental design for a refrigerated showcase, substantially as shown and described.
